HEADREST FOR A DENTAL CHAIR

James D. Chessrown, 4284 Stratford Road,
Youngstown, Ohio

Filed Aug. 28, 1964, Ser. No. 81,503

Term of patent 14 years

(Cl. D15—3)

FIG. 1

FIG. 2

FIG. 3

FIG. 4

FIG. 5

FIG. 6

FIG. 7

FIG. 8

FIG. 9

FIGURE 1 is a front elevational view of a headrest for a dental chair, showing my new design;

FIGURE 2 is a back plan view thereof;

FIGURE 3 is a top plan view thereof;

FIGURE 4 is an end elevation thereof;

FIGURE 5 is a front elevational view of the headrest of FIGURE 1 wherein a cover retaining snap-on ring is added thereto;

FIGURE 6 is a top plan view thereof;

FIGURE 7 is an end view thereof;

FIGURE 8 is an enlarged cross sectional illustration on line 8-8 of FIGURE 5 thereof; and

FIGURE 9 is an enlarged cross sectional detail on line 9-9 of FIGURE 5 thereof.

I claim:

The ornamental design for a headrest for a dental chair, as shown and described.
